United States Patent Office

Des. 230,418
Patented Feb. 19, 1974

230,418

LAMP

Paul E. Nelson, 223 Bluebird Drive,
Midwest City, Okla. 73110

Filed Feb. 15, 1973, Ser. No. 332,695

Term of patent 14 years

Int. Cl. D26—05

U.S. Cl. D48—20 R

FIG. 1 is a front elevational view of a lamp showing my design.

FIG. 2 is a left side elevational view thereof.

FIG. 3 is a top plan view thereof.

FIG. 4 is a cross-sectional view thereof, taken on the line 4—4 of FIG. 1.

FIG. 5 is a rear elevational view thereof.

FIG. 6 is a right side elevational view thereof.

FIG. 7 is a bottom plan view thereof.

FIG. 8 is an enlarged cross-sectional view thereof, taken on the line 8—8 of FIG. 1.

I claim:

The ornamental design for a lamp, as shown and described.
